LIGHTING FIXTURE

Norbert H. Schwenkler, Chicago, Ill., assignor to Patent License Corporation, Chicago, Ill., a corporation of Illinois

Filed Feb. 14, 1963, Ser. No. 73,563

Term of patent 14 years

(Cl. D48—23)

FIG. 1 is a perspective view of the fixture looking from below the same adjacent one end thereof;

FIG. 2 is a transverse section of the fixture as viewed generally along line 2—2 in FIG. 1; and

FIG. 3 is a fragmentary perspective of a corner portion of the lens panel of the fixture looking into the panel.

The dominant features of my design reside in the portions shown in full lines.

I claim:

The ornamental design for a lighting fixture, as shown and described.
